DESIGN FOR A GOLF CLUB

George E. Barnhart, Pasadena, Calif.

Application February 21, 1934, Serial No. 50,823

Term of patent 14 years

To all whom it may concern:

Be it known that I, GEORGE E. BARNHART, a citizen of the United States, residing at Pasadena, in the county of Los Angeles and State of California, have invented a new, original, and ornamental Design for a Golf Club, of which the following is a specification, reference being had to the accompanying drawing, forming part thereof.

In the drawing—

Fig. 1 is a side elevation illustrating the ornamental design of a golf club contemplated by this invention; and

Fig. 2 is a section on the line 2—2 of Fig. 1.
I claim:

The ornamental design for a golf club, as shown,

GEORGE E. BARNHART.
